UNITED STATES PATENT OFFICE.

ARTHUR H. GUSTAFSON, OF CHICAGO, ILLINOIS.

ENVELOP.

1,249,951.

Specification of Letters Patent. Patented Dec. 11, 1917.

Application filed March 27, 1917. Serial No. 157,852.

To all whom it may concern:

Be it known that I, ARTHUR H. GUSTAFSON, a citizen of the United States, and a resident of Chicago, in the county of Cook 5 and State of Illinois, have invented certain new and useful Improvements in Envelops; and I do hereby declare that the following is a full, clear, and exact description thereof, reference being had to the accompanying 10 drawings, and to the characters of reference marked thereon, which form a part of this specification.

This invention relates to improvements in safety envelops of that class wherein the 15 closing flap is interlocked to the body of the envelop in such a way that when said flap is closed and the interlocked parts of the body are engaged, the said flap can not be opened again without tearing the sheet from which 20 the envelop is made and thereby leaving traces which show that the envelop has been tampered with.

Among the objects of the invention is to provide a simple and effective envelop of 25 this character, which can be made at a cost not substantially greater than the ordinary sealed envelop, and a construction wherein the locking device on the closing flap and the envelop are not only certain in respect 30 to their locking action but are formed on or by parts which possess sufficient strength or ruggedness to withstand hard usage.

The invention consists in the combination and arrangement of the parts shown in the 35 drawings and described in the specification and is pointed out in the appended claims.

As shown in the drawings;

Figure 1 is a plan view of a blank from 40 which the envelop is made.

Fig. 2 is a side elevation of the envelop with the closing flap in its open position.

Fig. 3 is a fragmentary vertical section taken through the interlocked parts of the flap and envelop body.

The blank from which the envelop is made 45 comprises a main or central section 10, two end flaps 11, 11 a side flap 12 and a closing flap 13. The several flaps are joined to the central portion of the envelop blank along 50 fold lines indicated by the broken lines.

The end flaps 11 are of special form, each 55 comprising a wide inner portion having an oblique edge 14 which springs from the central portion of the blank at the fold line be- tween said central portion and the flap 12, and a relatively elongated terminal 15, the

upper edge of which extends in prolongation of the fold line between closing flap 13 and the main or central portion of the blank. The flap 12 is generally triangular as in 60 standard envelops. Instead of terminating in a sharp point, the terminal 16 of said flap has the form of a relatively short rectangular extension 16.

The closing flap 13 is formed at its outer 65 edge with a substantially rectangular extension 17, which is provided with end wings 18 and a side wing 19 that are joined to the extension along the fold lines indicated. Each of the said terminal portions 15 of the end 70 flap is provided with a slit 20, and at the ends of each slit is a triangular notch 21. The extension 16 of the flap 12 is likewise, provided with a similar slit 22 having end 75 notches 23.

In folding up the blank to produce the envelop the end flaps 11 are first folded inwardly over the central portion 10 of the blank with their elongated terminals or 80 wings 15 one over the other; and said terminals are of such length that each reaches a distance beyond the transverse center line of the envelop. Paste is applied to the overlapping parts of the end flap terminals so as to paste them together. Thereafter the 85 flap 12 is folded upwardly over the end flaps and is pasted at its oblique marginal portions 14 to the end flaps, the flap being gummed for this purpose; and the extension 16 is also pasted flat upon the overlapping 90 terminals 15 of the end flaps. When said terminals 15 and the extension 16 are thus assembled the several slits 20 and 22 are brought into register, as well also as are the 95 notches 23 at the ends of said slits. When said flaps are thus folded and pasted the slits 20 and 22 and the notches 21 and 23 are brought into registration to produce a through slit through the three ply wall of the envelop; and said three ply wall, thus 100 pasted, produces a sufficiently heavy wall structure at the slit to resist tearing out of the slit.

The end and side wings 18, 19, respectively, of the closing flap tongue or extension 17 are folded inwardly on said tongue in the way shown in Figs. 2 and 3 to produce a pocket 24 which opens inwardly toward the base of the flap, and the said wings are pasted together in their overlying parts. The multi layer construction produces a tongue of sufficient stiffness to en- 110

able it to be readily inserted into the slit of the envelop wall. Said pocket is of such width that it fits the lip formed in the multiple envelop wall above the locking slit so as to interlock with said lip, the notches 21, 23 permitting the pocket to slide over said lip. When inserting the tongue into the slit it is forced inwardly through the slit beyond its normal locking position so that the edge of the open side of the pocket, formed by the free edge of the wing 19, is caused to pass the locking lip of the slit, whereupon the said pocket bearing tongue is slightly withdrawn and the pocket springs open so that said free edge of the pocket interlocks with the lip of the slit, said free edge passing into the notches 21, 23. When the parts are so interlocked they can not be detached for the reason that the free edge of the pocket can not be made to pass the locking lip at the slit. Any successful attempt to release the locking tongue will therefore result either in tearing the tongue or the envelop wall at the end of the locking slit and leave evidence of tampering.

If desired, and especially with long envelops, small patches of gum 25 may be applied to the oblique margins of the closing flap so as to avoid opening of said flap away from the envelops when the flap is closed to such an extent as to permit other envelops in the mail bag entering beneath the flap margin in a manner tending to tear said flap.

The blank from which the envelop is formed also constitutes a feature of my invention as is hereinafter claimed.

It is to be understood that some variations may be made in the structural detail without departure from the spirit of my invention and that the invention is not limited to the specific detail shown except as to claims wherein such details are specifically set forth and as imposed by the prior art.

I claim as my invention:

1. An envelop having a closing flap provided with a locking tongue formed with a pocket that is closed at its ends and at one side and open at its inner side, the wall of said envelop being provided with a slit to receive said tongue and at one side of said slit with a lip which enters said pocket.

2. An envelop having a closing flap provided with a locking tongue formed with a pocket that is closed at its ends and at one side and open at its inner side, the wall of said envelop being provided with a slit to receive said tongue and at the ends of said slit with notches to form at one side of said

slit a lip to enter and interlock with said pocket.

3. An envelop having a closing flap and formed with a multiple wall, the plies of which are pasted together and pierced with a locking slit having at one side a locking lip, the closing flap being provided with a tongue to enter said slit, and said tongue being formed to provide a pocket which fits over and interlocks with said lip.

4. An envelop having a slit having at one side a lip, and a closing flap formed with a locking tongue to enter said slit, said tongue provided with end and side wings which are folded over the tongue in overlapping relation to each other and pasted together to form a pocket which interlocks with said lip.

5. An envelop comprising a main portion, two end and a side folding flap which are folded over the main portion and in overlapping relation to each other, and are pasted together at their overlapping portions, said flaps being provided with slits having notched portions at either end, said slits being adapted to register when the flaps are folded to constitute a reinforced locking slit, and a closing flap provided with a tongue to enter said slit and having members that are folded and pasted together to form a pocket to interlock with the edge of said slit, and with said notches.

6. The blank for the envelop described comprising a central section, three foldable sections provided with extensions each having a locking slit formed with notched portions at the end thereof to provide a lip on the upper edge of the slit, and a closing section provided with a pocket adapted for co-operation with said lips when the blank is assembled.

7. An envelop having a plurality of foldable sections adapted to be assembled to produce a multi-ply wall provided with a slit having a downwardly extending lip therein, and a closing section having an extension adapted for insertion through said slit, said extension being provided with a pocket adapted for the reception of said lip, whereby withdrawal of the said extension is prevented.

In witness that I claim the foregoing as my invention, I hereunto append my signature in the presence of two witnesses at Chicago, Illinois, this 26th day of March, 1917.

ARTHUR H. GUSTAFSON.
